(57) CLAIM

The ornamental design for a shelf display, as shown and described.

DESCRIPTION

FIG. 1 is a perspective view of a shelf display according to the invention;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view from one side thereof; and,

FIG. 7 is a side elevational view from the other side thereof. The broken-line disclosure of various elements in the views is for illustrative purposes only and forms no part of the claimed design.

1 Claim, 5 Drawing Sheets*Fig. 1Fig. 2Fig. 3Fig. 4Fig. 5Fig. 6Fig. 7*
